UNITED STATES PATENT OFFICE.

ROSS LEE BAKER, OF NEW YORK, N. Y.

BELT SUSPENSION FOR TROUSERS.

1,233,958.

Specification of Letters Patent. Patented July 17, 1917.

Application filed July 15, 1914, Serial No. 851,120.

To all whom it may concern:

Be it known that I, ROSS LEE BAKER, a citizen of the United States, residing at 60 Wall street, New York, in the county of New York and State of New York, have invented certain new and useful Improvements in Belt Suspension for Trouser; and I do hereby declare the following to be a full, clear, and exact description of the invention, such as will enable others skilled in the art to which it appertains to make and use the same.

This invention relates to the type of trousers supporters designed to obviate the necessity for the employment of suspenders.

Attempts have been made to employ a belt in lieu of suspenders, but because of the natural tendency of the belt to drop down and rest upon the hip bone, resulting in supporting the trousers too far below the waist line, it has become almost the universal practice to wear belts merely for appearance and to utilize suspenders in addition.

The primary object of this invention is to overcome the dropping of the trousers below the required line, while supported on a belt, whereby suspenders may be entirely dispensed with.

A more detailed object is the effective supporting of the upper edge of the trousers sufficiently high above the supporting belt that the belt may rest upon the hips of the wearer while sustaining the trousers at the desired elevation.

A still further object is the provision of simple and cheap belt supporting means for trousers constructed to allow the utmost freedom of movement of the wearer.

With these and further objects in view, as will in part become apparent and in part be stated, the invention comprises certain novel constructions, combinations and arrangements of parts as will be hereinafter specified and claimed.

In the accompanying drawings:

Figure 1 is a perspective view of a fragment of a pair of trousers having applied thereto an embodiment of the invention.

Fig. 2 is a view in side elevation of one of the suspension stays detached.

Fig. 3 is an edge view thereof.

Fig. 4 is a top plan view thereof.

Fig. 5 is a fragmentary vertical section taken centrally through one of the clasps.

Referring to the drawing by numerals, and particularly to Figs. 1 to 5, 1 indicates

a clasp adapted to grip the belt 2. To clasp 1 are pivoted arms 3, 3 which, with their clasps 4, 4 for the upper edge of a pair of trousers, seen at 5, make up one suspension stay. Each clasp 4 is pivoted to its arm 3 by a rivet in the same manner as is clasp 1. As all of said clasps are exactly alike only one is shown in detail, and does not require detail description since any appropriate clamp or engaging device may be used. That shown is in common use. Each arm 3 may be made longitudinally adjustable in various ways, but preferably by being formed of lapping sections having a series of bolt-receiving apertures 6 engaged by bolts 7. As many apertures 6 may be provided as desired, and bolts 7 are preferably caused to engage those apertures which are farthest apart for any given adjustment.

As best seen in Fig. 4, the upper terminal of each arm 3 is slightly twisted or bent laterally to cause the clasps 4 to assume a set corresponding angularly to the relation of the upper line of the trousers at the two points of engagement.

In addition to the relative adjustment of arms 3 rendered possible by apertures 6 and bolts 7, clasp 1 can be moved to a greater or less distance from the planes of clasps 4 merely by moving the free ends of arms 3 toward each other or apart. It will be further noted that, in operation, that portion of the trousers band between clasps 4 of one of the suspension stays serves as a tension member preventing lateral separation of the upper ends of the arms of the respective stay, lateral approach being resisted by the entire remaining portion of the trouser band, and the flexibility of the trouser band will naturally be such as to allow freedom for such play of the arms of the stay as will comport with the ease and comfort of the wearer during use.

In practice, the belt 2 is worn preferably within the trousers so as to be concealed, and is engaged by as many suspension stays as the wearer may prefer, three being ordinarily sufficient. In addition to the use of belt 2, an outside belt 8 may be worn for effect. Belt 2 resting on the hips of the wearer will effectively support the trousers at the desired elevation, and when adjusting the apparatus for the first time to a new pair of trousers, the wearer will, of course, adjust the relative location of the belt either

by adjusting bolts 7 or by placing clasps 4 closer or farther apart, or by both methods until the belt 2 rests comfortably in position for not sliding farther downwardly and at the same time sustains the trousers at the desired height.

In lieu of the clasps at the ends of the arms or bars of the several forms of stays, other connecting means may be employed 10 within the spirit and scope of the invention, and a very simple substitute would be an eyelet or aperture at each end of the respective bar adapted to be stitched to the trousers and belt.

15 What I claim is:—

1. A device for connecting trousers to a supporting belt, comprising a pair of arms connected together at their lower ends and diverging upwardly, a trousers engaging 20 element mounted upon the upper end of each arm and adapted for engagement with the upper edge portion of the trousers and to move with and upon the arms to accommodate the movements of the body, and a 25 belt engaging element mounted upon the lower connected ends of the arms for engagement with a belt to support the arms in upwardly diverging relation and admit of the free adjustment of the arms toward and 30 from each other.

2. A device for connecting trousers to a supporting belt, comprising a pair of arms pivotally connected together at their lower ends and diverging upwardly, a clamp piv-

otally mounted upon the upper end of each 35 arm and adapted for engagement with the upper edge of the trousers and to swing with and upon the arms to accommodate the movements of the body, and a third clamp pivotally mounted upon the lower connected 40 ends of the arms for clamping engagement with a belt to support the arms in upwardly diverging relation and admit of the free adjustment of the arms about their pivotal connection.

3. A device for connecting trousers to a supporting belt, comprising a pair of upwardly diverging arms pivotally connected at their lower ends, each of said arms comprising a pair of adjustably connected flat 50 bars, a clamp mounted upon the upper end of each arm and adapted to be secured to the upper edge of the trousers, and a third clamp mounted upon the lower connected 55 ends of the arms and adapted to be secured upon a belt, said upper and lower clamps being pivotally mounted upon the opposite ends of the arms to adapt the clamps to the flexing of the trousers and the belt, and said arms being adjustable to vary the spacing 60 of the belt from the upper edge of the trousers.

In testimony whereof I affix my signature in presence of two witnesses.

ROSS LEE BAKER.
